CRADLE SUPPORT FOR A CAMERA

Harry E. Mazur, Los Angeles, Calif.
(2280 Araby Drive, Palm Springs, Calif. 92262)

Filed June 10, 1970, Ser. No. 23,417

Term of patent 14 years

Int. Cl. D16—05

U.S. Cl. D61—1

FIG. 1 is a front elevational view of the cradle support for a camera showing my new design;

FIG. 2 is a top plan view thereof;

FIG. 3 is a rear view thereof; and

FIG. 4 is a side elevational view thereof.

I claim:

The ornamental design for a cradle support for a camera, substantially as shown.
